UNITED STATES PATENT OFFICE.

WILLIAM I. HALLOCK, OF CULVER CITY, CALIFORNIA, ASSIGNOR OF ONE-HALF TO
JOHN E. BEHME, OF EAGLE ROCK CITY, CALIFORNIA.

TABLE-ADJUSTING DEVICE FOR PLANERS AND THE LIKE.

Application filed July 19, 1924. Serial No. 726,994.

This invention relates to improvements in planers used in connection for surfacing lumber.

It has been a common disadvantage in planers that the table upon which the lumber to be surfaced is supported is of insufficient length for all purposes.

The primary object of this invention is to provide a simple and quickly attachable supporting or auxiliary table for a planer whereby lumber of considerable length will have sufficient surface upon which to rest while being run under the cutters.

A further object of this invention is to provide a planer or auxiliary table which will be automatically and simultaneously raised or lowered when the planer table is being vertically adjusted beneath the cutters.

With these and other objects in view which will be pointed out in the following detailed description and specified in the appended claims, reference is had to the accompanying drawings for an illustrative embodiment of my improvement, in which:

Figure 1 is a top plan view of a planer to which my auxiliary table has been attached,

Fig. 2 is a vertical section taken substantially on the line 2—2 of Fig. 1, the planer table and the auxiliary table being shown in lowered position,

Fig. 3 is a vertical section taken substantially on the line 2—2 of Fig. 1, the planer table and the auxiliary table being shown in elevated position;

Fig. 4 is a plan view, partly shown in section, both tables having been removed;

Fig. 5 is a plan view, partly shown in section, taken substantially on the line 5—5 of Fig. 3, and

Fig. 6 is a partial perspective of a modification.

Referring to the accompanying drawings, in which similar reference characters designate similar parts, the planer generally designated at P is provided with a base plate 10 having upstanding side walls 11 and 12, an upstanding front wall 13, and an integral upstanding rear portion 14. A pair of wedge-shaped members 15 rest upon the base plate 10 and are free to move backward and forward over its surface.

These wedge-shaped members 15 are connected by a cross bar 16, attachment being made thereto by means of jack screws or

bolts 17, and serve to support the body of a planer table 18. The planer table 18 has a flat surface 19 and a pair of opposite legs 20 provided with inclined straight lower surfaces 21 which rest and slide upon the inclined surfaces 22 of the wedge-shaped members 15. The planer table 18 is also provided with a pair of rollers 23 somewhat spaced apart, serving to support a piece of lumber L to be surfaced, above the flat surface 19 of the table. One or more rotary cutters C are mounted between the upstanding sides 11 and 12 and have their shafts journaled therein.

The upstanding front wall 13 houses a journal 24 for a jack screw 25 extending rearwardly from the upstanding front wall 13. The forward end of the jack screw 25 is provided with a hand wheel 26, and the jack screw proper is adapted to screw into a suitable block 27 secured to the cross bar 16, preferably on the under side thereof, by means of suitable bolts 28. The planer table is provided with suitable projections 29 extending through guide slots in the side walls 11 and 12 which limit the movement of the planer table to a strictly up and down motion.

Secured to the rear end of the planer table by means of bolts 30 are a pair of runners 31 and 32 across which are secured cross arms 33 serving to support the surface of the table as indicated at 34. The surface of the auxiliary table 34 is flush with the surface 19 of the planer table.

The rear upstanding member 14 has a horizontal extension 35 upon which is secured a pair of channelled or grooved members 36 and 37, the grooves being shown at 38 and 39 respectively. A pair of connecting rods 40 and 41 fit within the grooves 38 and 39 and are adapted to slide or roll longitudinally therein. The forward ends of these connecting rods 40 and 41 are secured to the cross bar 16 by means of bolts 42. The rearward ends of these connecting rods 40 and 41 have mounted thereon journals 43 and 44 respectively, housing a suitable shaft or axle 45, carrying pulley wheels 46 and 47 at each extremity.

The runners 31 and 32 have at their ends remote from the planer a pair of triangular blocks or supports 48 and 49 respectively, each of which blocks is provided with an inclined lower surface 50 and 51, adapted

to engage and rest upon the pulley wheels 46 and 47. It will be noted that the inclined surfaces 50 and 51 of the triangular supports 48 and 49 are in planes parallel 5 to the inclined surfaces 22 of the wedge-shaped members 15.

The extremities of the grooved or channelled members 36 and 37 remote from the planer are preferably provided with suitable legs or supports 53, and suitable braces 54 are connected to the mid-points of the channelled members 36 and 37 and to the 10 standing member 14 in the rear of the base plate 10. It is to be understood that when 15 the auxiliary table is of considerable length, the use of the legs 53 is of preferable construction, but if the auxiliary table is of a smaller dimension, the use of the braces 54 alone may be sufficient to support the 20 grooved or channelled members 36 and 37.

The operation of this device is as follows: Upon rotating the hand wheel 26, the jack screw 25 produces either a forward or backward movement of the block 27, causing 25 a forward or backward movement, as the case may be, of the cross bar 16. This action produces movement of the wedge-shaped members 15 and upon these members being moved rearwardly would cause the 30 planer table to be elevated. In a like manner, if the wedge-shaped members were drawn forwardly, the planer table will be allowed to be lowered because of gravity. Upon the cross bar 16 being moved rearwardly, the connecting rods 40 and 41 together with the axle or shaft 45 carrying the pulley wheels 46 and 47 will also be moved rearwardly an equal amount, the connecting rods 40 and 41 sliding within the grooves 35 or channels 38 and 39 of the members 36 and 37.

The rearward movement of the pulley wheels 46 and 47 which engage the lower inclined surfaces 50 of the triangular supports 48 and 49, will cause the rearward end 45 of the auxiliary table to be raised in a manner similar to that which causes the elevation of the planer table by the wedge-shaped members 15.

50 The converse is also true. When the cross bar 16 is moved forwardly, the wedge-shaped members 15 are also moved forwardly and the pulley wheels 46 and 47 are brought forwardly, all an equal amount. The movement 55 of the pulley wheels 46 and 47 and the movement of the wedge-shaped members 15 being in parallel planes and bearing upon inclined surfaces which are also in parallel planes, will cause the supports of both the planer table and the auxiliary table to be lowered an equal amount, thereby providing vertical adjustment of both the planer table and the auxiliary table simultaneously.

60 65 In view of the fact that the auxiliary

table is secured by bolts 30 and the channelled members 36 and 37 are secured to the horizontal extension 35 by bolts 30^a, it is apparent that the auxiliary table, when not desired, may be easily and quickly detached from the planer proper.

70 It is seen from the above that I have provided means for automatically and simultaneously vertically adjusting both the planer table and the auxiliary table by the 75 simple and single movement of the hand wheel 26.

In the modification shown in Fig. 6, a pair of horizontal rails 60 are substituted for the grooved or channelled members 36 80 and 37. The shaft or axle 45 has at its ends the pulley wheels 46 and 47 provided with flanges 46^a and 47^a respectively, which bear upon the inside faces of the triangular supports 48 and 49. A pair of rollers 61 are 85 loosely mounted upon the shaft 45 adjacent the pulley wheels 46 and 47. These rollers 61 are adapted to roll upon the rails 60. The connecting rods 40 and 41 are secured to the shaft 45 between the rollers 61, so that as these connecting rods are drawn rearwardly, the shaft 45 is drawn with them and has the rollers 61 rolling upon the rails 60. The pulleys 46 and 47 support and 90 roll under the inclined surfaces of the triangular plates 48 and 49 in identically the same manner as in the modification shown in Figs. 1 to 5. This modification is 95 designed to reduce the friction and reduce the force necessary to move the connecting rods 40 and 41 backward and forward to adjust the auxiliary supporting table.

100 It is to be understood that the attached drawings and the above description are used for illustrative purposes only and I limit myself only in the scope as defined by the 105 appended claims.

What is claimed is:

1. A planer having a table, means forming an inclined surface upon the under side of said table, a slidable wedge engaging said inclined surface, means for sliding said wedge to raise and lower said table, an auxiliary table detachably secured to said table, means forming inclined surfaces upon the under side of said auxiliary table, means engaging said inclined surface and supporting said auxiliary table, and means for actuating said means so as to raise and lower said auxiliary table.

110 115 120 125 130 2. A planer having a table, means forming an inclined surface upon the under side of said table, a slidable wedge engaging said inclined surface, means for sliding said wedge to raise and lower said table, an auxiliary table detachably secured to said table, means forming inclined surfaces upon the under side of said auxiliary table, and means engaging said inclined surface and supporting said auxiliary table connected to said wedge

whereby vertical adjustment of said table will cause simultaneous adjustment of the auxiliary table.

3. A planer having a table, wedges supporting said table, means for moving said wedges to vertically adjust said table, guides secured to the table, members movable upon the guides and connected to said wedges, an auxiliary table secured to said table, and means providing inclined surfaces for supporting said auxiliary table upon said members whereby when the table is vertically adjusted by said wedges, the auxiliary table will be adjusted with it.
15. 4. A planer having a table, wedges supporting said table, means for simultaneously moving said wedges so as to vertically adjust the table, an auxiliary table secured to said table, means providing inclined surfaces upon the under side of said auxiliary table, rollers engaging said inclined surfaces, and means connecting said rollers to said wedges, so as to move therewith, whereby adjustment of said table will produce adjustment of said auxiliary table therewith.
25. 5. A planer having a table, means providing an inclined surface upon the under side of said table, an auxiliary table detachably secured to said table, means providing an in-

clined surface upon the under side of the auxiliary table, which is parallel to the inclined surface on the planer table, supporting means engaging the inclined surfaces on said tables, and means for shifting said supporting means relatively to said tables, so as to simultaneously raise or lower said tables.

30. 6. An auxiliary table adapted to be applied to planers which have tables provided upon their under sides with inclined surfaces which are engaged by shiftable supports, said auxiliary table having an inclined surface on its under side adapted to assume a position parallel to the inclined surfaces on the planer table when the auxiliary table is applied thereto, supporting means engageable upon the inclined surfaces of the auxiliary table, said supporting means being shiftable relatively to said auxiliary table, and means for connecting said supporting means to the shiftable supports of the planer whereby the planer and auxiliary table may be simultaneously raised and lowered upon movement of the planer support.

In testimony whereof I have signed my name to this specification.

WILLIAM I. HALLOCK.
